FIG. 1.

FIG. 2.

INVENTOR
Harold E. Pollard

BY *John L. Morris*
ATTORNEY

UNITED STATES PATENT OFFICE

HAROLD EDWARD POLLARD, OF LONDON, ENGLAND, ASSIGNOR TO E. POLLARD & COMPANY LIMITED, OF LONDON, ENGLAND

AWNING

Application filed December 3, 1931, Serial No. 578,826, and in Great Britain March 28, 1931.

This invention relates primarily to window blinds of the awning type, but is applicable to sunshades or weather shades for purposes other than for the protection of windows.

In such apparatus the rail or lath at the free end of a sun-blind or the like is supported at each end by an arm which is made in two parts of substantially equal lengths 10 pivotally connected with each other, the ends of the lath or rail being supported at the end of the outer half. The other or inner half of each arm is pivoted at its inner end to permit it to be swung backwards, as for example, inwardly.

Means are provided whereby the outer half of the arm is swung backwardly upon its pivot when the inner half of the arm is swung upon its pivot, so that the outer part 20 of the arm is, as it were, folded against the inner part when the latter is swung backwards to the closed position for the sun-blind.

This result is attained according to the 25 present invention by providing a longitudinal guide on the inner half of the arm in which a sliding rack is movable, the rack engaging a pinion fast on the inner end of the outer part of the arm and pivoted on the 30 guide, this pivot forming the pivotal connection between the two parts of the arm. The sliding rack is actuated by means of a radius rod connected at one end therewith and pivoted at its other end at a point suitably displaced from the pivot axis of the 35 inner part of the arm. When the latter is swung inwardly upon its pivot, the rack is pushed outwardly relatively to its guide and the pinion and rotates the latter upon its 40 pivot, thereby swinging the outer part of the supporting arm so that it folds backwardly along the inner part thereof.

In the accompanying drawing Fig. 1 is a 45 plan showing one end of a sun-blind support in accordance with the present invention, with the top of the box or casing removed, and Fig. 2 is a transverse section through the box on line 2-2 of Fig. 1. In these figures the supporting arms are shown 50 in full lines as folded up within the box or

casing, that is to say in the position in which the blind is rolled up, and in dotted lines as partially extended or unfolded.

In these drawings A represents the rail or lath at the free end of a sun-blind or the like. 55 The rail A is supported at or near each end by a pivoted or jointed arm, the outer part B of each arm being connected with the lath at a convenient point along its length, as for example at B', by means of a pin and slot 60 connection. The inner end of the outer half B is pivotally connected with the inner half C of the folding arm as at the point C' near its outer end. The inner end of the part C of the folding arm is pivoted to a bracket D 65 within the fixed box or casing E, as at the point D', so as to enable it to be swung inwardly into the position shown in full lines in Fig. 1. The outer end of the inner part C of the folding arm is formed as or has secured 70 to it a guide C' in which a rack F is arranged to slide. This rack F engages a pinion B' formed on or secured to the inner end of the outer part B of the folding arm, and it is pivotally connected with the outer end of a 75 radius rod G, the inner end of which is pivoted as at G' within the box or casing and has an extension in the form of a segmental worm wheel G' which engages a worm H upon an actuating shaft I. 80

When the inner part C of the folding arm is swung inwardly upon its pivot D', the rack F is pushed outwardly relatively to its guide C', thereby rotating the pinion B' and causing the outer part B to swing upon the 85 pivot C', so that the arm folds backwardly under the inner part C of the folding supporting arm.

Having thus described the nature of the said invention and the best means I know of 90 carrying the same into practical effect, I claim:

1. In supports for awnings and the like in which the rail at the free end of the awning is supported at each of a plurality of points 95 by a pivoted arm comprising a pair of pivotally connected parts, means for effecting the pivotal movement of the outer part of each arm upon the inner part thereof, said means comprising a rack upon the inner part 100

- of the arm, a pinion upon the inner end of the outer part of the arm and engaging said rack, means for maintaining said pinion in engagement with said rack during relative movement of said rack with respect to said pinion, and means for producing relative movement between said pinion and rack, said last-named means comprising a radius rod having its outer end pivotally and slidably connected with that portion of the inner part of the arm on which said rack is formed and having its inner end pivoted on a fixed point, and means for swinging said radius rod about its inner pivot.
- 15 2. A support for awnings and the like according to claim 1, wherein the means for producing relative movement between the rack and pinion includes a member movable longitudinally of the inner part of the supporting arm and carrying the pivot of the outer end of the radius rod.
- 20 3. A support for awnings and the like according to claim 1, wherein the means for maintaining the pinion in engagement with the rack comprises a member slideable longitudinally of the inner part of the supporting arm and on which the pinion is journaled.

In testimony whereof I have signed my
30 name to this specification.

HAROLD EDWARD POLLARD.
